BODY RESTRAINT

Eleanor S. Baker, Bethesda, Md., assignor, by direct and mesne assignments, of one-sixth to Howard L. Rose and one-sixth to Harold J. Nussbaum, Washington, D.C.

Filed May 25, 1956, Ser. No. 587,376

8 Claims. (Cl. 128—134)

The present invention relates to restraining garments and, more particularly, to a restraining garment adapted to confine an individual to his bed without unduly restricting his movements.

Two types of body restraints are now in wide use but both types are unduly confining to the individual to which they are applied. One such restraint is the straight jacket which substantially completely immobilizes the patient and severely cramps the body. This type of restraint may be acceptable for the most violent type of patient but, in addition to the fact that it is unduly restricting, it has a depressing effect on the less violent and, therefore, more rational individuals. In addition, where a restraint is required merely for the purpose of retaining a non-violent patient in bed, the straight jacket is wholly unacceptable.

The other type of restraint commonly employed is individual limb restraints, that is, the individual's hands and arms are tied to the bed. This allows the patient a limited amount of movement but he is maintained on his back or front and in order to turn him he must be untied, rolled over and retied. An additional disadvantage of this type of restraint is that the arms and legs become irritated under the ties.

Consequently, neither type of restraint in general use today is necessary or conventional for use with mildly disturbed patients and they are wholly unsuitable where it is desired only to maintain an individual in bed.

It is an object of the present invention to provide a restraining garment which maintains a patient in bed but which does not restrict movement of the arms and legs and allows the patient to roll from side-to-side.

It is another object of the present invention to provide a restraining garment which may be adjusted to the size of the wearer.

It is yet another object of the present invention to provide a restraining garment having overlapping front sections secured together by a zipper and employing additional zipper halves disposed parallel one to the other so that the garment may be closed with varying degrees of overlap of the front sections to adjust the size of the garment to the size of the wearer.

It is still another object of the present invention to provide a restraining garment employing a vest-like garment for encircling the torso of the wearer which may have secured thereto two openable cuffs for restraining the arms of the wearer.

Yet another object of the present invention is to provide a restraining garment employing a vest-like member for encircling the body of the wearer, a half sheet and a plurality of straps for securing the vest-like member to the bed sheet and including straps for securing the half sheet to a bed, the latter straps being secured to metal rods sewed in the half sheet.

It is another object of the present invention to provide a restraining garment employing a vest-like member for enclosing the torso of the patient, the vest member including overlapping front sections which are secured to

2

gether by means of a zipper, the garment further including a locking arrangement to prevent opening of the zipper by the wearer.

The above and still further features, objects and advantages of the invention will become apparent upon consideration of the following description of several specific embodiments of the invention, especially when taken in conjunction with the accompanying drawings, wherein;

Figure 1 is a top view of the restraining garment of the present invention;

Figure 2 is a front elevation of the restraining garment; and

Figure 3 is a view of the restraining garment of the present invention equipped with arm-restraining cuffs.

Referring specifically to Figures 1 and 2 of the accompanying drawings, the restraining garment of the present invention includes a torso receiving vest 1 secured to a half sheet 2 by means of a first plurality of straps 3 and a second plurality of straps 4. The half sheet 2 has its left and right sides, as viewed in Figure 1, folded under and stitched to the body of the sheet to provide two longitudinally extending pockets 5 along the sides of the sheet 2. An elongated metal bar 6 is disposed in each of the pockets 5, the upper and lower ends of the pocket 5, as viewed in Figure 1, being stitched closed so as to retain the bars 6 in the pockets 5. Each of the pockets 5 are provided along the outer edges thereof with apertures 7, three being illustrated in each pocket for the purpose of example only. Each aperture 7 extends into the pocket 5 so as to completely expose the bar 6 in the region of the aperture. A strap 8 is associated with each of the apertures 7 in the left side of the sheet 2 and has a looped end through which the bar 6 extends, the strap 8 being thereby secured to the sheet 2. Associated with each aperture 7 on the right side of the sheet 2 is a buckle 10 carried on a strap 11 having a looped end 12 for receiving the bar 6. The half sheet 2 is adapted to be secured to a bed 13 having a mattress 14 as illustrated in Figure 2 of the accompanying drawings. The main body of the sheet 2 is disposed on the top of the mattress 14 with the sides carrying the pockets 5 extending over the side edges of the mattress. To secure the restraining garment to the bed, the straps 8 are passed under the spring and mattress and are received by the buckles 10, the straps 8 being drawn tight so that the sheet is firmly secured to the bed 13.

The torso receiving vest 1 is adapted to tightly fit the body of the wearer and includes a back member 16 and partially overlapping right and left front members 17 and 18. The vest 1 further includes a neck receiving aperture 19 and two arm holes 20 and 21. The front members 17 and 18 may be joined together by a zipper 22 having one element 23 sewn to the member 17 and another element 24 sewn to the member 18. In order to prevent an individual placed in the garment from undoing the zipper, two metal rings 25 and 26 are provided, the rings 25 and 26 being sewn or otherwise suitably secured to the lower edges of the members 17 and 18, respectively, adjacent the zipper 22. The zipper 22 includes a conventional slide operating handle 27 having an aperture 28 in the lower end thereof. The handle 27 extends through the rings 25 and 26 when the zipper is fully closed and a shackle 29 of a lock 30 is passed through the aperture 28 in the handle 27. The lock 30 is then closed and the zipper cannot be operated until the lock is opened and the shackle 29 removed from the aperture 28. In practice it has been found necessary to employ two rings 25 and 26, preferably although not necessarily fabricated from metal. If only a single ring is employed the zipper may be opened by pulling up on the handle and at the same time pulling up on the lower end of the front member 17 or 18 to which the

ring is secured. However, where two rings are employed, it is necessary to pull up simultaneously on the lower end of both members 17 and 18, an operation which is rendered impossible because the vest 1 is filled by the body of the wearer and there is insufficient material to allow such a maneuver. It is therefore necessary, in order to prevent the individual in restraint from operating the zipper and further to prevent him from sliding downward and out of the bottom of the vest, that the vest 1 fit the body of the wearer snugly. It is impractical in most hospitals and institutions to have a supply of garments to fit each different size individual that may be encountered. Consequently, it is desirable to have the garment readily adjustable in size within limits. This is accomplished in accordance with the present invention by providing additional elements 24' of the zipper 23, parallel to the element 24 and spaced transversely therefrom, only one additional element being illustrated. Thus the extent of overlap of the members 17 and 18 may be varied within limits in accordance with the size of the individual and, as a result, only a few standard sizes of the garment must be provided to accommodate many different size individuals.

The vest 1 is secured to the half sheet 2 by the two sets of straps 3 and 4. The straps 3 extend from the left side of the sheet 2, as viewed in Figure 1, under the vest 1 and are secured to its right side. The straps 4 extend from the right side of the sheet 2 under the vest 1 and are secured to its left side. The straps 3 and 4 are alternated along the length of the vest and are employed to allow the individual in restraint to roll from side-to-side, this feature being illustrated in Figure 2 where the vest 1 is illustrated as rotated toward the left of the drawing. The length of the straps 3 and 4 determine the angle through which the individual may roll and by selecting straps of sufficient length, the angle of roll may be as much as 180° in either direction.

The material from which the vest 1, straps 3 and 4 and half sheet are fabricated is determined primarily by the strength of the individual to be restrained. Where the individual is quite strong, the garment is made of canvas and the parts coming into contact with the body may be lined with a softer material to prevent irritation of the skin resulting from rubbing.

The present invention provides a restraining garment wherein the provision of a vest 1 which envelopes the torso of the wearer prevents him from rising to a sitting position and yet allows a maximum degree of side-to-side rolling movement. The vest 1 is readily adjustable to the size of the wearer as a result of the provision of plural zipper elements and the zipper is securely locked in the closed position by the handle 27, the rings 25 and 26 and the lock 30. The straps 8 and buckles 10 are securely fastened to the sheet 2 by the bars 6 which bars prevent the sheet 2 from being torn from the bed.

The garment illustrated in Figures 1 and 2 may be employed in cases where it is desirable to maintain a person in bed in the prone position. It is not suitable for restraint of violent cases since the arms of the wearer are free and may strike at attendants or tear at the body of the wearer himself. The garment illustrated in Figures 1 and 2 may be made suitable for use with violent individuals by the addition of arm restraints 31 and 32, as illustrated in Figure 3 of the accompanying drawings.

The arm restraints 31 and 32 are secured to the front members 17 and 18, respectively, the restraint 31 being illustrated in the closed position and the restraint 32 being illustrated in the open position. The restraints are elongated perpendicular to the zipper 22 and comprise a flat canvas or leather panel 33 stitched or otherwise suitably secured to the front members 17 and 18. The upper and lower edges of the panel 33 are each provided respectively with the two elements of a zipper 35 and when the arm of the individual is placed on the panel 33, it is folded about the forearm above the wrists

and the zipper 35 closed, the hands of the wearer lying one on top of the other adjacent the lower end of the chest. The sheet 33 fits snugly about the forearm and is smaller than the wrists and hands of the wearer thereby preventing him from withdrawing his arms.

The arm restraints 31 and 32 may assume a different position from that illustrated in Figure 3 and may extend inwardly and downwardly of the vest 1. This arrangement may be preferable since the inner portions of the arm restraints 31 and 32 would extend below the vest 1 and would cause less interference with the additional elements 24 of the zipper 22. Additionally, the arm restraints may terminate in bag-like members so as to enclose the hands of the wearer and prevent him from tearing at his body in the vicinity of his hands or at one hand with the other. It is apparent that by the addition of the arm restraints 31 and 32, the restraining garment of the present invention becomes wholly acceptable for use with violent patients. The arm restraints may be applied to all of the garments and may or may not be used as required by the needs of the patient and, consequently, the garment becomes an all purpose restraint. The heavy duty zipper for closing the vest is sufficiently strong to withstand the strain that can be applied to it by most persons of average strength. In the event that the garment is to be applied to an individual of greater than average stress who might be able to pull the vest closing zipper apart, hooks such as the type employed on children's raincoats, may be substituted for the zipper and protected by a zippered flap.

While I have described and illustrated several specific embodiments of the present invention, it will be clear that variations of the specific details of construction may be resorted to without departing from the true spirit of the invention as defined in the appended claims.

What I claim is:

1. A body restraining garment comprising a wide band, belt means for securing said wide band to a bed, a vest means for encircling a portion of the body of a patient and having arm holes and a neck hole, said vest means including two front sections having adjacent longitudinally extending edges, a zipper having first and second elements secured to the edges of said front sections, additional zipper elements being secured to one of said front sections and displaced one from the other transversely of the edges of said front sections, and a plurality of straps securing said vest means to said wide band, said straps occupying parallel planes, first ends of adjacent straps being secured to opposite sides of said vest means, said straps extending under said vest means and second ends of said straps being secured to said wide band outwardly from said vest means.

2. The combination in accordance with claim 1 wherein said zipper includes a slide and an apertured handle for operating said slide, said garment further comprising two rings each secured to corresponding ends of a different front section adjacent the longitudinal edges thereof, the apertured portion of said handle being adapted and arranged to extend through said rings when said zipper is closed.

3. The combination in accordance with claim 1 further comprising two flexible panels secured to said vest means adjacent the lower end thereof, each of said panels having separable zipper elements secured to opposite edges thereof, said panels being adapted to form sleeves surrounding the forearms of the patient.

4. The combination in accordance with claim 1 wherein said belt means include two elongated bars, pocket means in said wide band for receiving said elongated bars, said pocket means having a plurality of apertures for exposing portions of said bars, a plurality of belts each secured to an exposed portion of one of said bars and a plurality of buckles each secured to an exposed portion of the other of said bars.

5. A body restraining garment for humans comprising a wide band, means for securing said wide band to a support, vest means for encircling a portion of the body of a patient and having arm holes and a neck hole, said vest means including longitudinally extending unconnected edges, closing means for securing said edges one to the other and comprising first and second separable means, said first separable means being secured to said vest means adjacent one edge thereof, said second separable means being secured to said vest adjacent said other edge thereof, additional second separable means spaced transversely of said edges from said first mentioned second separable means, means for preventing the patient from opening said closing means, and a plurality of straps securing said vest means to said wide band, said straps occupying parallel planes, first ends of adjacent straps being secured to opposite sides of said vest means said straps extending under said vest means and second ends of said straps being secured to said wide band outwardly from said vest means.

6. A body restraining garment comprising a wide band, means for securing said wide band to a bed, a vest means for encircling a portion of the body of a patient and having arm holes and a neck hole, said vest means including two front sections having adjacent longitudinally extending free edges, a zipper having first and second elements secured to the edges of said front section, at least one additional second zipper element spaced from and parallel to the aforesaid second zipper element, zipper engaging means for locking said zipper in its closed position, and a plurality of straps securing said vest means to said wide band, said straps occupying parallel planes, first ends of adjacent straps being secured to opposite sides of said vest means, said straps extending under said vest means and second ends of said straps being secured to said wide band outwardly from said vest means.

7. A body restraining garment for humans comprising a wide band, means for securing said wide band to a support, vest means for encircling a portion of the body of a patient and having arm holes and a neck hole, said vest means including longitudinally extending unconnected edges, closing means for securing said edges one

to the other and comprising first and second mutually engagement separable means, said first separable means being secured to said vest means adjacent one edge thereof, said second separable means being secured to said vest adjacent said other edge thereof, additional second separable means spaced transversely of said edges from said first-mentioned second separable means, means for preventing the patient from opening said closing means, and a plurality of straps securing said vest means to said wide band, said straps occupying parallel planes, first ends of adjacent straps being secured to opposite sides of said vest means said straps extending under said vest means and second ends of said straps being secured to said wide band outwardly from said vest means.

8. A body restraining garment for humans comprising a wide band, means for securing said wide band to a support, vest means for encircling a portion of the body of a patient and having arm holes and a neck hole, said vest means including longitudinally extending unconnected edges, closure means for securing said edges one to the other, said closure means comprising first and second interconnectable and separable means, said first separable means being secured to said vest means adjacent one edge thereof, said second separable means being secured to said vest adjacent said other edge thereof, additional second separable means spaced transversely of said edges from said first-mentioned second separable means, and a plurality of straps securing said vest means to said wide band, said straps occupying parallel planes, first ends of adjacent straps being secured to opposite sides of said vest means, said straps extending under said vest means and second ends of said straps being secured to said wide band outwardly from said vest means.
